JOINT AND PLIER CONSTRUCTION

Max Schiffbauer, 60 Warner Ave., Springfield, N.J.

Filed Aug. 19, 1957, Ser. No. 679,047

2 Claims. (Cl. 81—416)

This invention relates to pliers, nippers and like instruments having two halves pivotally connected together and adapted to be operated by manipulation of their handles, of the type disclosed in my Patent No. 2,611,288 upon which the present invention is an improvement.

It is an object of this invention to improve the quality of plier performance by providing for and adapting to the mesh joint construction a mesh plate of circular shape and suitable toughness which by means of its shape and mechanics results, (a) in constant uninterrupted contact of all meshing or guiding surfaces involved to their maximum capacity which in turn produces maximum support for the performing operation of the pliers; (b) a mesh-plate that is designed to rotate or float and has only in this condition the largest possible wearing surface comprising the full circle of three hundred sixty degrees but may upon demand easily be transformed into a stationary one.

It is another object of the invention to gain for the entire performing operation of the pliers guidance and rigidness, employing the full extent of the joint, in addition to the one transmitted by the pivot rivet and derive therefrom the opportunity to narrow down the joint portion of the two plier halves to such an extent where suitable dimensioned bar stock, and for smaller instruments even wire, unforged, but both halves bent and machined to receive each other, will produce acceptable stable joints and tools with substantial savings.

It is a further object of this invention to provide for pliers, nippers and similar instruments produced from bar stock or wire, wherever it is required, ring or bow handles or grips of suitable material in a substantial and economic fashion.

It is still another object of this invention to effect further savings in preparing the components of the pliers and simplify the assembling of mesh joints by omitting accurately matched shapes and machined press fits to facilitate the fastening of the mesh plate as well as its selective positioning into the assembly; neither does the joint require assembling under red heat, avoiding resulting distortions and their correction.

For other objects and for a better understanding of the invention, reference may be had to the following detailed description taken in connection with the accompanying drawings, in which

Fig. 1 is a plan view of a pair of pliers according to the preferred embodiment of the present invention, shown in opened position;

Fig. 2 is a plan view of one component plier half of a modified form of pliers;

Fig. 3 is a plan view of said modified pair of pliers in closed position; and

Fig. 4 is a side elevational view of a pair of pliers according to Fig. 3.

Similar numerals refer to similar parts throughout all the views.

Referring now more particular to the drawings, 10 and 11 designate complementary plier halves perforated

and adapted to be pivotally connected together. The parts 10 and 11 being substantially identical, have a jaw portion 12 and a handle portion 13 integral therewith and made from a single piece each. They have a flat bearing surface or portion 14, and an opening or perforation 17 extends through the center of this bearing portion 14.

The bearing surface 14 is being extended, diametrically opposite, by undercuts 15 into the jaw portion 12 and 16 into the handle portion 13. These undercuts 15 and 16 are of such width as to receive with a slide fit the round guide or mesh plate 18, and of such depth as to allow rotating or floating of the mesh plate 18, and are finished at such angle as to permit the insertion and location of the mesh plate 18. If, however, the demand is for a stationary mesh plate, then the mesh plate 18, after first insertion and location into the joint assembly, may be fastened or pinched by compressing the undercuts 15 and 16 of only one of the two plier halves 10 or 11.

20 The mesh plate 18 is of circular shape and perforated in the center to register with the pivot rivet 19. This perforation is so dimensioned as to provide a running fit permitting, if so elected, the rotation or floating of the mesh plate 18 in the joint assembly. The mesh plate 18 is inserted, without requiring specific predetermined positioning except registering its perforation with the holes 17 in the two component halves 10 and 11, into the undercuts 15 and 16 of the joint assembly and held in position by the insertion of the pivot rivet 19 into the assembly.

25 After the assembly is thus completed, portions of the mesh plate 18 will reach with a slide fit into the undercuts 15 and 16, effecting thereby the harnessing of the opening and closing movements of the two plier halves 10 and 11 to the same plane, resulting in stabilization for these movements and rigidness for the jaw portion 12 under working stresses. The circular shape of the mesh plate 18 will engage the undercuts 15 and 16 uninterrupted in their entire length throughout the entire performance of the pliers as may be gathered by comparing the relative positions of mesh plate 18 and undercuts 15 and 16 in Figs. 1 and 3; by comparing these specific details it will also become obvious that the circular mesh plate 18 by nature of its shape cannot but transmit these stabilizing qualities to the full extent of its diameter which coincides with the capacity for the joint; it will also have in its rotating or floating form wearing surfaces, being in mesh with the undercuts 15 and 16, comprising its entire three hundred sixty degrees.

30 With the movements of the plier halves 10 and 11 stabilized or guided throughout, the joint portion of these halves 10 and 11 consisting of portion 14 Fig. 2, with its adjoining areas, may be narrowed down from the width typical for the conventional forgings to permit the use of bar or wire stock suitably dimensioned, unforged, but bent and machined to receive each other, the modified Z form in Fig. 2, giving one example, with the joint still providing satisfactory rigidness for pliers, nippers and like instruments.

35 60 The ring or bow handle 20, Fig. 3, is fabricated separately and fastened by a suitable method at points 21 and 22, Fig. 3, to the operating half 10 and 11.

I claim:

1. In a plier or similar tool comprising complementary parts, each of said parts having jaw and handle portions, said jaw and handle portions of each part having like reentrant recesses arranged diagonally opposite each other, a mesh plate having an edge portion adapted to cooperate with the respective reentrant recesses of the parts, and a pivot pin connecting the complementary parts and the guide plate together, the improvement which comprises said edge portion having a curvilinear

periphery continuous for an angular extent greater than the maximum opening of the jaws, and said mesh plate has a clearance in said recesses with respect to both of said complementary parts about said pivot pin as a center of rotation to form a floating mounting.

2. In a plier or similar tool comprising complementary parts, each of said parts having jaw and handle portions, said jaw and handle portions of each part having like re-entrant recesses arranged diagonally opposite each other, a mesh plate having an edge portion adapted to cooperate with the respective reentrant recesses of the parts, and a pivot pin connecting the complementary parts and the guide plate together, the improvement which comprises said edge portion having a curvilinear periphery continu-

ous for substantially 360° about the center of the pivot pin as a vertex, and said mesh plate has a clearance in said recesses with respect to both of said complementary parts about said pivot pin as a center of rotation to form 5 a floating mounting.
